UNITED STATES PATENT OFFICE.

JOSEPH HANCK, OF BALTIMORE, MARYLAND.

GAS-BURNER FOR HEATING PURPOSES.

SPECIFICATION forming part of Letters Patent No. 391,606, dated October 23, 1888.

Application filed March 2, 1888. Serial No. 265,999. (No model.)

To all whom it may concern:

Be it known that I, JOSEPH HANCK, a subject of the Emperor of Germany, residing at Baltimore, in the State of Maryland, have invented 5 certain new and useful Improvements in Gas-Burners for Heating Purposes, of which the following is a specification.

My invention relates to a gas-burner for heating purposes. The device is adapted for 10 heating cooking utensils or anything else to which it is desired to apply heat, and for heating an apartment.

The invention is illustrated in the accompanying drawings, in which—

15 Fig. 1 is a side view of the gas-burner. Fig. 2 is a vertical section of the lower part. Figs. 3 and 4 are top and bottom views, respectively, of the flame-plate. Fig. 5 shows two views of the gas and air spreader plate. 20 Fig. 6 is a view of one of the diaphragms. Figs. 7 and 8 are views of two additional perforated diaphragms.

The gas-burner has a base, *a*, of any suitable shape. A gas and air receiving chamber, 25 *B*, is immediately above the base. A mixing-chamber, *C*, is above the receiving-chamber, and is provided on top with a flame-plate, *D*, and a contracted throat, *e*, connects the receiving-chamber and mixing-chamber. The said 30 throat *e* is provided with a packing, *e'*, of plaster-of-paris filled in around the inner tube of said throat to form a solid foundation between the lower and upper chambers, *B*, *C*. The base *a* has an internal vertical pipe, *f*, provided 35 with a lateral branch air-inlet, *f'*, and an ordinary gas-burner or jet-aperture, *g*, has position within the said vertical pipe *f*, whose lower end is closed. Gas is supplied to the jet-aperture *g* by a pipe, *g'*.

40 Immediately above the vertical pipe *f* is a gas and air spreader plate, which consists of a flat circular flange, *h*, having perforations *h'*, and a central imperforate downward-pointing cone, *i*. The inverted cone *i* points down directly over the vertical pipe *f*. As the gas escapes from the jet-aperture *g* and ascends the pipe *f*, air is drawn in at the lateral branch *f'*. Both air and gas are deflected by the point *i* of the spreader-plate and caused to ascend 45 through the perforations *h'*. One or more perforated diaphragms, *j*, between the spreader- 50

plate and contracted throat *e*, serve to partly mix the gas and air.

The mixing-chamber *C* is funnel-shaped—that is, it spreads and widens from the throat *e* up to the flame-plate *D*. Within the lower part of the chamber *C* is located a double cone, *C'*, the smaller portion of which fits the upper portion of the contracted throat, so as to direct the gas and air through the opening at 60 the apexes of the double cone centrally into the upper cone-section. To insure the more thorough admixture of the gas and air, the upper portion of the cone *C'* in the mixing-chamber *C* is provided with perforated dia- 65 phragms *k*, *k'*, *k''*, as many as may be deemed advisable. It will be noticed that the lower dia- phragms are provided with small diffused per- forations *l*, the object of which is to compel the air and gas in ascending to take zigzag or cir- 70 cuitous paths, so as to insure its uniform ad- mixture. The diaphragm *k''* is provided with a large central perforation, *l'*, to direct the mixed gas and air centrally and directly be- 75 low the flame-plate.

The flame-plate *D* is provided on its lower surface with division-flanges *m*, which form passage or spaces *n*, while the top surface of the plate has gas-holes *o* from the said passages or spaces. The passages or spaces *n* on the 80 lower side of the flame-plate are ring-shaped or concentric in the present instance. They may, instead of being separate, be spiral or a continuous winding around. This is immaterial.

The top of the mixing-chamber *C* has a rim- 85 flange, *p*, and on the inner side thereof an an- nular seat, *q*. The flame-plate *D* sets down in- side of said rim-flange, and thus it may be re- moved at any time to afford access to the in- 90 terior.

The admixed gas and air passing the holes *o* in the flame-plate *D* is burned on the upper surface of said plate, and produces a blue flame of great intensity of heat.

The division-flanges *m* give the desired 95 amount of metal to the flame-plate where heat is stored, which heats the gas and augments the intensity of the heat from the flame. It also causes flame to issue from all the holes alike by producing an equal pressure of gas at all 100 of the holes.

A superheater comprises a cylinder, *R*, open

at the top and bottom and having perforations *s* in its walls. This sets upright upon the flame-plate D, as shown in Fig. 1. In operation the air may enter the perforations *s*, and the interior of the cylinder R will be a mass of blue flame. A vessel or cooking utensil placed above the upper end of the cylinder R will be heated at once. Should the vessel be of sufficient size to entirely close the cylinder R, the said vessel may be supported in any suitable manner a short distance above said cylinder.

By this device a high degree of heat is obtained from the consumption of the minimum amount of gas.

I do not limit my invention to the precise construction shown, as certain of the parts may be altered, changed, or omitted without materially affecting the invention.

Having described my invention, I claim and desire to secure by Letters Patent of the United States—

A gas burner having in combination a base, *a*, provided with a vertical pipe, *f*, having an air-inlet, *f'*, and a gas-jet, *g*, a chamber having an inverted cone, *i*, immediately above the said pipe *f*, the said chamber terminating at the top with a contracted throat, *e*, a mixing-chamber, C, supported above said throat and provided with diaphragms *k* *k'*, having small perforations *l*, and a diaphragm, *k²*, having a central opening, *l'*, and a perforated plate on top of the mixing-chamber, substantially as specified.

In testimony whereof I affix my signature in the presence of two witnesses.

JOSEPH HANCK.
